UNITED STATES PATENT OFFICE.

SAM AMBLER, OF BRADFORD, ENGLAND.

SPINDLE APPARATUS FOR RING-SPINNING AND LIKE FRAMES.

Application filed November 30, 1926, Serial No. 151,679, and in Great Britain February 24, 1926.

This invention relates to improvements in connection with the spindle apparatus to take the place of the usual flyers, cap, and ring, and the like spindle apparatus, that is, 5 in that class of spinning frame where the spindle is dead, and carried from a lifter rail, and the bobbin or the like is mounted on a tube driven by a wharl. My object is to arrange and combine with the spindle and 10 the driven tube means for increasing the ease of running and consequently enabling an increase of speed to be obtained, and a much larger bobbin to be employed.

My invention is in the nature of a bearing 15 between what is known as a cap tube and the top of a solid spindle, from which bearing the tube is supported. The bearing may take the form of a ball interposed between the top of the spindle and an upper 20 bearing fitting, carried by the tube, or the spindle may be coned to rest in a bearing carried by the tube, or the tube may carry a coned or pointed bearing member to take into a hollow in the spindle end or the top. 25 Lubricating means will be provided, the lower end of the tube or wharl portion will not bear on the base or rail. The ring used will be fixed as to position and the spindle will be carried on a lifter rail.

30 Referring to the drawings which form a part of this specification—

Fig. 1 represents a sectional elevation of a tube on a spindle according to one form of my invention.

35 Fig. 2 represents an elevation and plan of a top bearing referred to.

Fig. 3 represents a sectional elevation of a modified form of tube supporting device.

40 Fig. 4 represents a plan and sectional elevation of a modified bearing member.

Fig. 5 represents a plan of a suitable ring holding device, and

Fig. 6 represents a detail of a ring adjusting device.

45 To carry my invention into effect, the cap tube T which is carried by the wharl W is continued upwards to or slightly beyond the top of the solid spindle S which latter is carried by a lifter rail L and the upper end of 50 the tube is closed, preferably by a removable bearing piece B, and between this piece and the top of the spindle which is suitably shaped, I in one form (Fig. 1) mount a ball O. Thus the spindle supports the ball, 55 and the ball the tube, and the lower edge T' of the tube T or wharl fitting dips into a

suitable oil well or reservoir C, but does not contact with the base thereof. Guard walls such as C' may be carried either from the 60 wharl, or oil reservoir.

These walls may be stepped as at C² to receive a dished washer C³ placed above the lubricant to prevent same being forced out by centrifugal force and to act as a guide to return any oil from above the washer to the 65 reservoir.

The tube T encloses the spindle S and the latter may have a spiral groove or grooves G cut therein, one or more apertures or cuts T² leading from the outer to the inner face 70 of the tube towards the base in order to provide efficient lubricating means, although I do not confine myself to this exact form.

In Fig. 3 the spindle may be pointed or coned as at S³ and the bearing member B 75 have a coned aperture B' through which the point S³ may project.

The bearing member B and the tube and ball are by preference so constructed that the ball will be retained in the tube when 80 same is removed from the spindle according to one method; the tube may be so constructed by flanging, dimpling or the like just below the centre of the ball, that the ball will be retained in the top.

With a removable top bearing B means will be provided for its easy removal from the tube, such as dimples or the like B² Fig. 4 capable of being engaged by a suitable tool, and in all cases apertures or cuts 90 such as B³, preferably central, will be formed to give passage for air, see Figs. 1, 2 and 4.

The ring R is of the fixed type either carried by a rail in the ordinary manner, or 95 preferably carried by a ring clip R', which clip is adjustably mounted by a spindle R⁴ in a bearing R² suitably mounted in connection with a fixed part of the machine. The clip R' is divided as at R³ and is provided with securing means such as R⁴. By using a ring holder of this type, different sizes of rings may be quickly adapted. The bearing R² may also be adjusted laterally, 100 see Fig. 6.

With anti-friction devices of the kind described and supporting the tube from the top, the tube being driven around a dead spindle mounted on a lifter rail, steady running and increased speed as well as efficient spinning are obtained at all reasonable speeds, whether they be high or low. 110

Large bobbins may be employed and increase of length of yarn produced without knots, further there is a considerable saving of time due to the periods of doffing being less frequent, and there is a saving of time in the twisting and winding operations.

I am aware that it has been heretofore proposed to carry bobbins or live spindles on dead spindles by means of anti-friction 10 bearings between the top of the spindle and bearings carried by the bobbin or live spindle. The spindles have generally been hollow and in some cases have been provided with external spiral grooves to assist lubrication of the bearings, whereas in my combination I combine with a dead spindle mounted on a lifter rail, a driven cap tube supported on bearings from the top of the 15 spindle, the tube operating within a stationary ring and thus with one apparatus 20

obtain the effect of ring, cap, or fly, spinning.

I claim:—

In a spinning frame, the combination of a lifter rail, a dead solid spindle supported thereby, a cap tube mounted for rotation on said spindle, a single bearing disposed between the spindle and the tube at their upper ends, said bearing communicating with the atmosphere, and an oil reservoir encircling a portion of the spindle and enclosing the lower end of the tube, said spindle being provided with a spiral groove communicating with said reservoir and adapted to convey oil from the reservoir to the bearing between the spindle and tube. 25 30 35

In testimony whereof I have signed my name to this specification.

SAM AMBLER.
